United States Patent

Des. 240,422
Patented July 6, 1976

240,422

TRACK FOR SUSPENSION OF DATA BINDERS

Walter Feldmahr, Highland Park, Ill., assignor to
Acco International Inc., Chicago, Ill.

Filed Dec. 17, 1974, Ser. No. 533,680

Term of patent 14 years

Int. Cl. D19—99

U.S. Cl. D19—99

FIG. 1 is a side elevational view of a track for suspension of data binders embodying my new design;

FIG. 2 is a top plan view thereof;

FIG. 3 is a bottom plan view thereof; and

FIG. 4 is an end elevational view.

I claim:

The ornamental design for a track for suspension of data binders, substantially as shown.
